(57) **CLAIM**

The ornamental design for a tool for alleviating ice freeze-up of vehicle window, as shown and described.

DESCRIPTION

FIG. 1 is a perspective view of a tool for alleviating ice freeze-up of vehicle windows showing my new design;
FIG. 2 is a front view of the tool for alleviating ice freeze-up of vehicle windows showing my new design;
FIG. 3 is a back view thereof;
FIG. 4 is a top view thereof;
FIG. 5 is a bottom view thereof;
FIG. 6 is a right side view thereof; and,
FIG. 7 is a left side view thereof.
